UNITED STATES PATENT OFFICE.

GEORGE W. STORMS, OF KALAMAZOO, MICHIGAN, ASSIGNOR OF ONE-HALF TO AUSTIN H. LONG, OF CRAWFORDSVILLE, INDIANA.

COLLAPSIBLE CULVERT-FORM.

1,344,775.

Specification of Letters Patent. Patented June 29, 1920.

Application filed October 25, 1919. Serial No. 338,243.

To all whom it may concern:

Be it known that I, GEORGE W. STORMS, a citizen of the United States, and a resident of the city of Kalamazoo, in the county of 5 Kalamazoo and State of Michigan, have invented certain new and useful Improvements in Collapsible Culvert-Forms; and I do hereby declare that the following is a full, clear, and exact description of the 10 same, reference being had to the accompanying drawings, and to the numerals of reference marked thereon, which form a part of this specification.

This invention relates to culvert forms 15 adapted to support a wooden frame while concrete or masonry is applied to the outside thereof.

One of the principal objects of my invention is to provide an improved form 20 which can be instantly collapsed and withdrawn after the monolithic structure has hardened and set.

Another object is to provide means for 25 readily adjusting the frame so that not only its width but also its height may be changed as desired.

Other and further important objects of 30 this invention will be apparent from the disclosure in the specification and accompanying drawings.

The invention (in a preferred form) is illustrated in the drawings and hereinafter more fully described.

On the drawings:

Figure 1 is an end elevation of my improved form.

Fig. 2 is a plan view of the same.

Fig. 3 is a section on the line 3—3 of Fig. 1.

Fig. 4 is a section on the line 4—4 of Fig. 1.

Fig. 5 is a detail perspective view of a part of the supporting frame.

Fig. 6 is a detail view on an enlarged scale 45 of a portion of the frame shown in Fig. 4.

Fig. 7 is a section of a modified form of construction.

Fig. 8 is a partial end elevation of a modified form of construction.

As shown in the drawings:

The culvert form comprises a frame 1, composed of side bars 2, preferably of angle

iron from each end of which cross bars 3 extend inwardly. These cross bars are pivotally connected at 4 to the side bars and are 55 arranged to overlap the cross bars opposite thereto. Each cross bar is provided with a series of bolt-holes 5, so that it may be pivotally connected to its overlapping cross bar by a bolt 6 at any desired point corresponding to the width of the culvert to be formed. 60

The bolts 6 also pivotally connect the cross-bars 3 to a longitudinal draw bar 30 so that by pulling on the latter the cross bars may be brought into the position shown in 65 dotted lines in Fig. 1. Thus movement of the cross bars brings the side bars 2 together and therefore away from the wooden frame work temporarily supported by the culvert frame 1.

To each side bar side supports are pivotally attached. Each side support comprises a bar 7 having one end pivotally attached at 8 to brackets 9 secured to the side bars 2 as shown in Fig. 4. The opposite ends of these bars 7 are similarly attached to the side bars by brackets 10.

One half of each bar 7 is arranged to extend perpendicularly to the side bar for the purpose of slidably carrying a bar 11 while 80 the other half extends diagonally therefrom to act as a brace for the first half and the bar 11 carried thereby. Each bar 7 is provided with a pair of laterally extending lugs 12 which are bent so as to slidably embrace 85 the bar 11 as shown in Fig. 1. A slot 13 is provided in the bar 7 in which a bolt 14 passing through the lower end of the bar 11 may slide. By tightening the nut on the bolt 14, the bar 11 may be held in any desired position relatively to the bar 7.

The top of the frame is formed of cross-pieces 15, pivotally connected at 11^a to the bars 11. Each cross-piece is arranged to overlap the opposite cross-piece so that the 95 width of the frame may be adjusted as desired.

To hold the cross-pieces 15 and thereby the bars 7 and 11 in position a supplementary supporting frame 16 is provided. This 100 frame comprises a pair of angle bars 17 rigidly connected at each end by bars 18. This supporting frame is arranged to rest on and slide freely on the cross bars 3 of the main

frame. U-shaped supports 19 are pivotally connected at 20 to the angle bars 17 so that they may fold down onto the lower part of the frame 16 when the device is collapsed for 5 withdrawal from the culvert.

Each support 19 comprises bars 21 between which a U-shaped member 22 is adapted to slide. Connecting rings 23 hold the bars 21 and the member 22 in sliding 10 engagement while set-screws 24 in each ring enable the parts to be locked in adjusted position. The upper ends 25 of the member 22, are notched for engagement with the cross-pieces 15 as is also provided with a 15 series of notches 26 along its lower edge for engagement with the upper end 25 of the member 22. The width of the top of the culvert form may therefore be varied as desired by moving the cross-pieces so as 20 to bring the proper notch 26 into engagement with the part 25.

It will be seen that the upper ends of the bars 11 and outer ends of the cross-pieces 15, are beveled so that the bars 11 25 may be inclined inward without projecting any part of either of these members beyond the outer surface of the other member.

Spreading of the ends 25 is prevented by means of a connecting strap 27 secured to 30 the member 22 and the bars 21 by pins 28. A U-shaped member 29 is mounted centrally on the strap 27 for further holding the cross-pieces 15 in position.

In Fig. 8 a modified form of construction is shown adapted for the formation of crowned culverts. In this case the cross-pieces 15^a are of arcuate form instead of straight. These cross-pieces 15^a are supported by means of a frame 31 adapted to 40 engage notches 26^a in the lower edges of the cross-pieces 15^a in the manner described in connection with Figs. 1 to 7. This frame 31 is connected to the upper ends of the bars 21 by pins 28.

45 The operation is as follows:

The culvert form is adjusted to the desired size, erected and the wooden forms placed therearound. Concrete is then placed around the wooden forms and allowed to 50 set.

The frame is then collapsed and for this purpose the supporting frame 16 is first folded up by drawing on the cross member 18 of that frame which allows the ends 25 55 of the member 22 to disengage themselves from the cross-pieces 16 when the member 22 is free to fall.

Next the cross-pieces 15 are allowed to drop and at the same time the side members 60 7 and 11 are swung inwardly so that these parts assume the position shown in dotted lines in Fig. 1. In that position the top and upper side boards may be removed.

Finally the draw bar is pulled to bring 65 the side bars 2 together when both the main

frame 1 and the supporting frame 16 may be removed entirely and the remaining boards removed from the interior of the completed culvert.

I am aware that various details of construction may be varied through a wide range without departing from the principles of the invention, and I therefore do not purpose limiting the patent granted otherwise than necessitated by the prior art. 70 75

I claim as my invention:

1. A device of the kind set forth comprising a pair of longitudinal side bars, members pivoted thereto each including a perpendicular portion and a diagonal brace 80 portion, additional members slidably mounted on the perpendicular portions, cross-members for connecting the side bars together and means for holding the first members in adjusted angular position relatively 85 to the side bars.

2. A device of the kind set forth comprising a pair of longitudinal side bars, members pivotally connected thereto, a cross piece extending inward from the top 90 of each member and overlapping the cross piece from the member opposite thereto, a supporting frame for said cross-piece, having a notched portion at its upper end for engagement with one or other of a series 95 of notches in the lower edge of one of the cross pieces and cross members connecting the side bars together.

3. A device of the kind set forth comprising a pair of longitudinal side bars, members pivotally connected thereto adjustable 100 in length, a cross piece extending inward from the top of each member and overlapping the cross piece from the member opposite thereto, a supporting frame for said 105 cross pieces adjustable in height to correspond with the length of said members and cross members connecting the side bars together.

4. A device of the kind set forth comprising a pair of longitudinal side bars, members pivoted thereto each including a perpendicular portion and a diagonal brace 110 portion, additional members slidably connected to the perpendicular portions, cross-members for connecting the side bars together, a cross piece extending inward from the top of each member and overlapping the cross-piece from the member opposite thereto, and a vertically adjustable support- 115 120 ing frame for said cross-pieces.

5. A device of the kind set forth comprising a pair of longitudinal side bars, members pivoted thereto each including a perpendicular portion and a diagonal brace 125 portion, additional members slidably connected to the perpendicular portions, cross-members for connecting the side bars together, a cross piece extending inward from the top of each member and overlapping the 130

cross-piece from the member opposite thereto, a supporting frame for said cross-pieces, having a notched portion at its upper end for engagement with one or other of a series of 5 notches in the lower edge of one of the cross-pieces, and cross members connecting the side bars together.

In testimony whereof I have hereunto subscribed my name in the presence of two subscribing witnesses.

GEORGE W. STORMS.
